UNITED STATES PATENT OFFICE

2,018,020

VENTILATOR

Rudolph H. Guenther, Chicago, Ill.

Application October 24, 1934, Serial No. 749,778

2 Claims. (Cl. 98—68)

This invention relates to improvements in ventilators of the rotary type, and is particularly adapted, though not necessarily limited in its use, to be attached to chimneys or draft pipes, and one of the objects of the invention is to provide an improved device of this character embodying a hood having a vane of substantial size attached thereto, whereby the mouth or open side of the ventilator will be always kept from the wind, thereby insuring that the same will be rain and storm proof, with the further result that down drafts will be impossible.

A further object is to provide improved means for mounting the hood.

15 A still further object is to provide an improved form of construction of hood.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

25 Figure 1 is a front elevation of a device of this character constructed in accordance with the principles of this invention.

Figure 2 is a side elevation of Figure 1.

Figure 3 is a view taken on line 3—3, Figure 30 1, from the bottom of the device.

Figure 4 is a vertical sectional view taken on line 4—4, Figure 1.

Figure 5 is a plan view of a blank from which the hood shown in Figures 1 to 4 is constructed.

35 Figure 6 is a view similar to Figure 5 of another form of hood, that is a hood of a larger size and constructed in two pieces.

Figure 7 is a detail front elevation of a portion of a hood shaped from the blank shown in Figure 6.

40 Figure 8 is a detail sectional view taken on line 8—8, Figure 7.

Referring more particularly to the drawings, the numeral 10 designates generally a supporting base constructed of any suitable material and preferably of annular configuration. Arranged within the base are ribs 11 having their ends secured to the base and with portions 12 abutting for a substantial length adjacent the diametric center of the base to provide a bearing for an upright member 13. This member 13 is preferably provided with a threaded extremity 14 which is seated in a bearing formed between the abutting portions 12 of the ribs, and nuts or collars 15 are provided on the threaded portion on oppo-

site sides of the ribs to secure the upright 13 in position and to provide a means whereby the upright may be adjusted in directions lengthwise of its longitudinal axis.

The abutting portions 12 of the ribs may be secured together in any suitable manner, such as by means of fastening devices 16.

The upper extremity of the upright 13 is preferably conical or tapered as at 17 to form an end bearing.

10 The numeral 18 designates generally a blank constructed of any suitable material such as sheet metal or the like and may be provided with reinforcing ribs 19 upstruck from the material and disposed adjacent but spaced from the peripheral edge of the blank. Additional reinforcing ribs 20 may also be provided in the blank.

The blank is shaped to form a hood having an open bottom 21 and an open side 22 and the blank is shaped or bent along the lines 23 to 20 form the body portion of the hood and also along the lines 24—25 to form a vane 26 integral with the hood. The portions 27 of the blank which form the vane 26 are brought together and in contact as shown more particularly in Figure 1, 25 and these portions 27 may be secured together in any desired or suitable manner, such as by means of a fastening rivet 28. The vane thus constructed will be disposed centrally with respect to the hood and with the open side 22 and 30 the vane serves as a means, when acted upon by the wind, to always maintain the open side 22 of the hood away from the wind, thereby insuring that no down drafts will be created through the hood and also that the elements will be prevented from entering the hood.

The hood thus formed may be of any desired size and when of an exceptionally large size, the blank forming the hood instead of being constructed of a single piece of sheet material as 40 disclosed in Figure 5, may be formed of two blanks 29—30, as disclosed in Figures 6 to 8. In this form of the invention, one-half of the hood will be formed by each of the blanks and a portion of the blank 29 may be shaped to form one 45 part of the vane as at 31, and a portion of the blank 30 may be shaped to form another portion of the vane as at 32. These vane portions are respectively bent or shaped along the lines 34, so that when the blanks are assembled, the portions of the blanks forming the vane will be brought together with their faces in contact, as shown more clearly in Figure 7. One of the vane portions, such as the portion 32, is preferably of a width greater than the other portion 31 so that 50 55

the edge 35 thereof may be flanged or bent over the edge of the other vane portion. The parts when thus assembled may be secured together by means of fastening devices 36, such as rivets or the like.

5 The body of the hood is shaped from the two blank sections 29—30 by being bent or shaped along the lines 37 to form the base of the hood, similar to the blank shown in Figures 1 and 2 and being bent upon the lines 23.

10 The edges 38—39 of the body portions of the blanks are overlapped as shown more clearly in Figure 8, and are secured together by means of fastening devices 40.

15 The hood whether thus formed of a single blank or of sections secured together will be shaped to form a skirt or depending portion 41 at the lower end, and reinforcing horizontal ribs 42 may be provided, if desired. The skirt or depending portion 41 is of an internal diameter greater than the external diameter of the base 10 and overhangs the base for a substantial distance, when the hood is in position and as the hood is rotated about an upright axis, the bottom 20 of the hood will move about the base member 10.

25 The hood is supported by means of a bracket arranged internally thereof, and the bracket is of such a construction that the tapered or reduced end 17 of the upright 13 will have a bearing thereagainst, and the upright 13 will be maintained out of direct contact with any portion of the hood, thereby prolonging the life of the device and preventing the bearing end of the upright 13 from wearing its way through the body 30 of the hood.

35 The bracket preferably consists of an upright member 43 constructed preferably of a strip of metal having a laterally projecting lower portion 44 provided with a flange 45 which contacts with the inner face of the wall of the hood and is secured thereto by a suitable fastening device 46. At the upper end of the member 43 is a laterally projecting portion 47 extending in a direction opposite to the direction of the portion 44 and terminates adjacent the top of the hood and in proximity to the base of the vane. A cross member 48 is secured to the extremity of the portion 47 of the bracket and this member 48 contacts with the inner face of the hood at the top thereof and the hood is secured to the member 48 in any suitable manner, such as by means of fastening devices 49.

40 A hollow upright frame member 50 also preferably constructed of suitable material, such as metal, is secured to the upright portion 43 of the bracket by means of fastening devices 51 and the frame member 50 is provided with spaced upper and lower parallel members 52—53 while a bearing member 54 is arranged within the frame member 50 and is secured in position by means of suitable fastening devices 55, and one of the fastening devices 51. The member 54 is spaced between the members 52 and 53 and is parallel thereto and forms with the lower member 53 a bearing through which the upright 13 freely passes. The tapered extremity 17 of the upright 13 contacts with the lower face of the upper member 52 of the frame 50 and this upper member 52 is preferably spaced from the portion 47 of the upright 43 and also of the member 48.

45 It will thus be manifest that the hood will be supported by the bracket construction and the bracket construction itself is supported by the upright 13 so that the hood will be free to rotate upon the upright 13 and all danger of wear

5 between the end of the upright 13 and the body of the hood will be obviated, thereby prolonging the life of the device. At the same time the hood will be supported by a single point bearing, rendering the same very sensitive to the action of the wind.

10 The bracket being of an open frame construction will also prevent the accumulation of foreign particles as the air or smoke currents passing through the bottom of the hood and out of the open side will keep the bearing clean.

15 A lug or pin 56 may be provided to extend through the upright 13 within the frame 50 to serve as a means for preventing accidental displacement of the hood.

If desired, the base 10 may be anchored by means of guy wires, and to that end there may be provided any desired number of openings 57 in the base, by means of which brackets may be secured to the base, and to which brackets the 20 ends of the anchor wires may be secured. If desired, one end of the anchor wire may be threaded through the opening 57 and secured.

20 The structure thus described may be secured in position in any suitable manner, either over an opening or the base 10 may be telescoped over the end of an upright pipe, and in which latter case the edges of the ribs 11 will contact with and rest upon the edge of the pipe.

25 The ribs 11 are comparatively narrow with relation to their height and are so arranged that the lower edges thereof will terminate a substantial distance above the lower edge of the base 10 so as to provide for the telescoping of the base 11 over the end of an upright pipe.

30 With this improved construction it will be manifest that the vane being formed integral with the hood and being arranged in the manner disclosed, will always insure the open side of the hood being positioned away from the wind, with the result that the elements will not enter the hood and down drafts will be avoided.

35 Furthermore, with this construction the necessity of ball bearings will be dispensed with and the hood will be free and sensitive to move about its pivot bearing 17, with the further result that the danger of the supporting bearing 17 wearing through the body of the hood will always be obviated.

40 Furthermore, the hood is mounted upon a one-point suspension, thereby reducing friction as the members 53 and 54 serve only as guides through which the upright 13 passes, and all stress and strain will be exerted upon the reduced extremity of the upright 13.

45 While the preferred forms of the invention have been herein shown and described, it is to be understood that various changes may be made in the details of construction and in the combination and arrangement of the several parts, within the scope of the claims, without departing from the spirit of this invention.

50 What is claimed as new is:—

55 1. A ventilator of the character described embodying a supporting base, a hood separate from the base and having an open side and an open bottom, the latter encompassing the base, a supporting member within the hood, said member comprising an upright portion of substantial length and laterally projecting arms extending from the ends of said portion in opposite directions, means securing the respective arms to the hood, a bracket carried by said upright portion of the supporting member and comprising spaced superposed and substantially parallel bearing 60

members laterally projecting from the supporting member, said bearing members also spaced from the said arms, and a stationary upright spindle secured to said base, said spindle passing 5 loosely through one of the bearing members and having an end bearing with the other of said bearing members, the bearing points of said spindle with said bearing members being intermediate and spaced for a substantial distance from the 10 ends of said arms.

2. A ventilator of the character described embodying a supporting base, a hood separate from the base and having an open side and an open bottom, the latter encompassing the base, a supporting member within the hood, said member comprising an upright portion of substantial length and laterally projecting arms extending from the ends of said portion in opposite directions, means securing the lower arm to the hood, 15

a cross member of substantial length secured to and projecting laterally from the upper arm to provide an extended supporting contact with the hood, means securing said cross member to the hood, a bracket carried by said upright portion 5 of the supporting member and comprising spaced superposed and substantially parallel bearing members laterally projecting from the supporting member, said bearing members also spaced from the said arms, and a stationary upright 10 spindle secured to said base, said spindle passing loosely through one of the bearing members and having an end bearing with the other of said bearing members, the bearing points of said spindle with said bearing members being intermediate and spaced for a substantial distance 15 from the ends of said arms.
